UNITED STATES PATENT OFFICE.

FREDERICK B. LANGSTON, OF NEW YORK, N. Y.

BOAT CONSTRUCTION.

1,003,364.

Specification of Letters Patent. Patented Sept. 12, 1911.

Application filed August 17, 1907. Serial No. 388,940.

To all whom it may concern:

Be it known that I, FREDERICK B. LANGSTON, a citizen of the United States, and a resident of the borough of Brooklyn, county 5 of Kings, city and State of New York, have invented certain new and useful Improvements in Boat Construction, of which the following is a specification.

This invention relates to boat construction.

In its broad aspect, the object of the invention is to reduce the resistance of the water to the progress of a boat.

The invention is applicable to many types 15 of craft including slow moving craft, such as canal boats, and fast moving craft, such as motor boats and the like.

More specifically it is the object of this invention to provide means for confining 20 gas so as to provide a layer of gas of material thickness beneath a supporting surface for a boat, so that the supporting surface is held up out of contact with the water and so that the confined layer of gas, which is in 25 direct contact with the water, will serve efficiently as an intermediate lubricating medium due to its low viscosity.

It is also an object of the invention so to construct the water contacting parts of the 30 boat that they will co-operate effectively with the confined layer of gas to reduce the resistance of the water to the progress of the boat and to utilize the reaction from the water against the moving water-contacting 35 parts automatically to prevent lateral tilting such as rocking. The furtherance of this object is contemplated by eliminating or minimizing all water-plowing or laterally-water-displacing surfaces and substituting 40 in their place water-skidding surfaces having only downward and forward reaction against the water when sliding or skidding over its surface.

To these ends the provisions of means for 45 forming one or more chambers each for holding and confining in all lateral directions a layer of air of material thickness beneath the surface of the boat is contemplated. In the embodiment of such means 50 a plurality of forward and aft extending parallel keel-like partition plates together with fore and aft-cross closures are contemplated to confine the gas under flat supporting surfaces.

55 It is also an object of the invention to

provide for the maintenance of a body of gas within the chamber under the supporting surface or surfaces.

The means by which the above and further objects of the invention are attained will be apparent from the following description, when read in connection with the accompanying drawings, and will be pointed out in the appended claims.

Reference should be had to the accompanying drawings which form part of this application, in which like numerals designate corresponding parts in the several figures, and in which,

Figure 1 is a fore and aft sectional elevation of a boat embodying features of this invention; Fig. 2 is a bottom plan view of the boat shown in Fig. 1; Fig. 3 is a sectional elevation taken through line 3—3 of Fig. 1 and looking in the direction of the 75 arrows; Fig. 4 is a similar view to Fig. 1 but showing a modified construction; Fig. 5 is a bottom plan view of the construction shown in Fig. 4; Fig. 6 is a sectional elevation taken through line 6—6 of Fig. 4 80 and looking in the direction of the arrows; Fig. 7 is an enlarged fragmentary sectional elevation showing an aft skidding member; Fig. 8 is an end elevation of the parts shown in Fig. 7 but with the middle portion broken 85 away; Fig. 9 is a detail section showing the fore closure of the means for confining in closed position.

Referring now more in detail to the drawings and more particularly to Figs. 1, 2 90 and 3,—1 designates a hull which is provided with a portion having an under-supporting surface 2. This portion may be a part of the hull or may be suitably secured thereto in any convenient manner. It is 95 preferable that this surface 2 be horizontal when the boat 1 is in normal position. Parallel side plates are illustrated extending fore and aft throughout the length of the hull. These partition plates are depressed below the supporting surface 2, are indicated by numerals 3 and 4 and are co-extensive in length with the length of the supporting surface 2. A fore-cross-closure 5 cross connects the side plates. An aft-cross-closure 6 also cross-connects the partition-plates. A rectangular caisson-like chamber 7 is completed by the partition-plates and the fore- and aft-cross-closures. This chamber is designed to retain a layer of suitable 100 105 110

gas such as air, such layer being of material thickness, between the supporting surface 2 and the underlying water 8. Thus, the side-plates and the cross-closures together constitute means for confining in all lateral directions a layer of gas of material thickness beneath the supporting surface.

Means for forcing a supply of such gas into the chamber 7 is shown in the form of 10 the pump 9 and the reservoir for compressed gas 10 which is connected with the pump through the valve 11. The tank 10 discharges into the chamber 7 by means of the duct 12 controlled by the valve 13. It is 15 contemplated that the tank 10 may be replaceable and removable and when charged with gas, under pressure constitutes, itself, means for supplying a source of gas for the chamber 7.

20 At the prow of the boat an upwardly inclined water-skidding member 14 is provided, the rear end of which constitutes the fore-cross-closure 5 and the rear lower edge of which is depressed, as shown, below the 25 supporting surface 2. The lower surface of this water-skidding member is shown curved but it is to be understood that the invention contemplates broadly a fore-water-skidding member, every cross section through the 30 under surface of which member is a horizontal straight line. This feature in connection with the under-surface of the fore-skidding plane 14 may be described otherwise by stating that this under-surface is 35 cylindrical, (the word cylindrical being used in its broad geometric sense) and every element of this cylindrical surface is a horizontal straight line.

In the drawings the side plates 3 and 4 40 are shown respectively having portions 17 and 18 extending below the lower edge of the fore-cross-closure 5 and continuing into portions 15 and 16 extending forwardly along and depressed below the under surface 45 of the fore-skidding member 14. Thus, as shown in Figs. 1 and 3, these fore- and aft-extending portions 15, 16, 17 and 18 extend downwardly below the lower surface of the 50 water contacting face of the fore-skidding member 14. By this location they serve as keels to steady the progress of the boat.

The junction between the under-surface 19 of the aft cross-closure 6 and the supporting surface 2 is suitably sealed as by the 55 flexible flap 21 shown in the drawings as covering the hinge 20 securing the member 6 to the hull. The under surface 19 of member 6 is shown flat throughout a considerable 60 extent and at its extreme aft portion, curved. Like the under surface of the fore skidding member 14, every cross section through this under-surface 19 of the aft skidding member 6 is a horizontal straight line.

65 One purpose for this formation of the

under surface of the water skidding members is to provide stability for the boat construction. Any rocking of the boat tends to depress one side or the other of these skidding members more than the other side, 70 causing a greater immersion on the side depressed. There is consequently a greater upward re-action from the impact of the water due to the progress of the boat on the side immersed the greater amount, which 75 tends automatically to right the boat.

The aft skidding member 6 is shown provided with keel plates 23 and 24 which form substantially continuations of the side plates 3 and 4. The aft skidding member 6 is provided with means for adjusting this angular position about the hinge 20. This means is indicated by the numeral 22 and shown in the form of a screw, the adjustment of which may be read from the scale 25. The steering of the boat may be accomplished in any suitable manner as by means of the rudder 26 and its co-operating manipulating mechanism.

In Figs. 4, 5, 6, 7, 8 and 9 modifications 90 are shown especially adapting the invention to its embodiment in motor boats. The parts bearing similar reference characters in these figures are the same as those previously described in connection with Figs. 1, 95 2 and 3. In addition it should be noted that a suitable source of power shown in the form of a combustion motor 27 is provided for driving the propeller 28 through the medium of the propeller shaft 30, the propeller being protected by means of the guard 35. The propeller shaft 30 is extended forwardly through the clutch 29 to a modification of the pump 9 and specifically 100 to a blower 9', which communicates with the reservoir 10' formed as a bulk head in the fore parts of the boat. The air intake for the blower 9' is indicated by 31 and is directed forwardly. This intake may be sealed by means of the valve 32, which is 105 serviceable in case of accident or when the motor 27 is not operating, to provide buoyancy for the boat structure. In this embodiment a part of the fore cross closure is formed by means of a cross partition or 110 valve 5' hinged to the boat structure by the hinge 33 and provided with a spring 34 tending to hold this valve closed, but yielding against the blast of air delivered by the 115 blower 9' and directed aftwardly into the 120 chamber 7.

During the progress of the boat the layer 125 of air between the supporting surface 2 is of such thickness as to constitute a real layer of material thickness which by reason of its low viscosity allows the supporting surface or surfaces of the boat structure to pass over the under-lying surface of the water 8 entirely without cohesion between the water and the supporting surfaces and 130

in such a manner that the relative movement between these surfaces is retarded merely by the low viscosity of the layer of air.

5 In the motor boat construction the propeller 28 is of such a construction and is driven at such a speed as to propel the craft at a high rate of speed. It has been found that high rates of speed tend to 10 drag the air in the chamber 7 aftwardly and out under the aft skidding member 6. This aftwardly escaping air serves to lubricate the aft skidding member 6 and necessitates continual air in chamber 7. This is accomplished by means of the blower 9' the 15 aftwardly directed blast from which, by reaction against the underlying water 8, aids, in a degree, in forwardly propelling the boat structure.

20 In connection with slow moving craft such as that illustrated in Figs. 1, 2, and 3 the renewal of air for the chamber 7 is not of so great necessity as is the case with high speed craft and in some cases it is 25 necessary to supply renewals merely sufficient to supply the leakage through the parts forming the walls of the chamber 7.

It is to be understood that the illustrations of the embodiment of this invention 30 are diagrammatic in a large degree and that it is contemplated that approved modern boat construction be employed in the embodiment of the various parts.

What is claimed and what is desired to 35 be secured by United States Letters Patent is:—

1. In a boat construction, a hull having an under supporting surface; a plurality of parallel, fore-extending side plates projecting beneath said supporting surface; an 40 upwardly inclined fore skidding-member with its rear lower edge depressed below said supporting surface and cross-connecting said side plates; and an aft skidding-member with its under surface inclined aftwardly and downwardly from said supporting surface and cross-connecting said side plates, every cross section through the 45 under surfaces of both said skidding-members being a horizontal straight line.

2. A boat construction comprising, a portion providing a substantially rectangular supporting surface; means forming a chamber and for confining in all lateral directions a layer of air of material thickness beneath said surface, said means comprising parallel side plates and fore- and aft-cross-closures; said aft-cross-closure being formed by a downwardly and rearwardly extending water-skidding-member; a fore 55 water-skidding-member extending forwardly and upwardly from the lower edge of said fore-cross-closure, every cross section through the under surfaces of both said water-skidding-members being a horizontal straight line; parallel keel portions projecting downwardly from both water-skidding-members and from the said side plates and below the 60 said layer of air; propelling means for the boat; and means for forcing gas into the chamber within said means for confining.

65 3. A boat construction comprising, a portion providing a substantially rectangular supporting surface; means forming a chamber and for confining in all lateral directions a layer of air of material thickness beneath said surface, said means comprising parallel side plates and fore- and aft-cross-closures; said aft-cross-closure being formed by a downwardly and rearwardly extending water-skidding-member; a fore water-skidding-member extending forwardly and upwardly from the lower edge of said fore-cross-closure, every cross section through the under surfaces of both said water-skidding-members being a horizontal straight line; parallel keel portions projecting downwardly from both water-skidding-members and from the said side plates and below the said layer of air; propelling means for the boat; and means for forcing gas into the chamber within said means for confining.

4. A boat construction comprising, a portion providing a substantially rectangular supporting surface; means forming a chamber and for confining in all lateral directions a layer of air of material thickness beneath said surface, said means comprising parallel side plates and fore- and aft-cross-closures; said aft-cross-closure being formed by a downwardly and rearwardly extending water-skidding-member; a fore water-skidding-member extending forwardly and upwardly from the lower edge of said fore-cross-closure, every cross section through the under surfaces of both said water-skidding-members being a horizontal straight line; parallel keel portions projecting downwardly from both water-skidding-members and from the said side plates and below the said layer of air; propelling means for the boat; and means for forcing gas into the chamber within said means for confining.

5. A boat construction comprising, a portion providing a substantially rectangular supporting surface; means forming a chamber and for confining in all lateral directions a layer of air of material thickness beneath said surface, said means comprising parallel side plates and fore- and aft-cross-closures; said aft-cross-closure being formed by a downwardly and rearwardly extending water-skidding-member; a fore water-skidding-member extending forwardly and upwardly from the lower edge of said fore-cross-closure, every cross section through the under surfaces of both said water-skidding-members being a horizontal straight line; parallel keel portions projecting downwardly from both water-skidding-members and from the said side plates and below the said layer of air; propelling means for the boat; and means for forcing gas into the chamber within said means for confining.

6. A boat construction comprising, a portion providing a substantially rectangular supporting surface; means for forming a chamber and for confining in all lateral directions a layer of air of material thickness beneath said surface, said means comprising parallel side plates and fore- and aft-cross-closures; said aft-cross-closure being formed by a downwardly and rearwardly extending adjustable water-skidding-member; a fore water-skidding-member extending forwardly and upwardly from the lower edge of said fore-cross-closure, every cross section through the under surfaces of both said water-skidding-members being a horizontal straight line; and means for forcing gas into the chamber within said means for confining.

7. A boat construction comprising, a portion providing a substantially rectangular supporting surface; means for forming a chamber and for confining in all lateral directions a layer of air of material thickness beneath said surface, said means comprising parallel side plates and fore- and aft-cross-closures; said aft-cross-closure being formed by a downwardly and rearwardly extending adjustable water-skidding-member; a fore water-skidding-member extending forwardly and upwardly from the lower edge of said fore-cross-closure, every cross section through the under surfaces of both said water-skidding-members being a horizontal straight line; parallel keel portions projecting downwardly from both water-skidding-members and from the said side plates and below the said layer of air; propelling means for the boat; and means for forcing gas into the chamber within said means for confining.

8. A boat construction comprising, a portion providing a supporting surface 2; a

fore water-skidding-member 14; means for confining in all lateral directions a layer of air within the chamber 7, said means comprising parallel side plates 3 and 4, aft-cross-closure in the form of the adjustable water-skidding-member 19, and a fore-cross-closure 5 forming a valve; means 22 for adjusting the inclination of the water-skidding-member 19; a motor 27; a propeller 28; 10 and an air blower 9' for forcing an aft-wardly directed stream of air into the chamber 7.

7. A boat construction comprising, a portion providing a supporting surface 2; a 15 fore water-skidding-member 14; means for confining in all lateral directions a layer of air within the chamber 7, said means

comprising parallel side plates 3 and 4, an aft-cross-closure in the form of the adjustable water-skidding-member 19, and a fore closure 5 forming a valve; keel portions 15, 16, 17, 18, 23, and 24; means 22 for adjusting the inclination of the water-skidding-member 19; a motor 27; a propeller 28; and an air blower 9' for forcing an aft-wardly directed stream of air into the chamber 7.

In testimony whereof, I have signed my name to this specification, in the presence of two subscribing witnesses.

FREDERICK B. LANGSTON.
